UNITED STATES PATENT OFFICE.

PETER COOPER HEWITT, OF NEW YORK, N. Y., ASSIGNOR TO COOPER HEWITT ELECTRIC COMPANY, A CORPORATION OF NEW YORK.

OPERATION OF TRANSLATING DEVICES WITH MULTIPLE ELECTRODES.

1,052,056.

Specification of Letters Patent. Patented Feb. 4, 1913.

Application filed May 23, 1903. Serial No. 158,456.

To all whom it may concern:

Be it known that I, PETER COOPER HEWITT, a citizen of the United States, and resident of New York, county of New York, State 5 of New York, have invented certain new and useful Improvements in Operation of Translating Devices with Multiple Electrodes, of which the following is a specification.

It is well understood that when electric 10 current traverses a divided circuit containing only ohmic resistance, the product of the current and the resistance in both branches is the same. In such a circuit it is not generally difficult to make an even division of 15 the load or, in other words, to make the fall of potential in both paths exactly the same.

The problem of running similar translating or transmitting devices in parallel becomes more difficult when the devices to be 20 operated are either such that the drop is practically independent of the current flowing, as, for example, in the gas or vapor electric apparatus patented to me in certain of its embodiments September 17, 1901, or such 25 that the resistance decreases more or less rapidly with increments of current, as in the well-known Nernst lamp. Under such circumstances, it is practically impossible to so construct the similar translating or trans- 30 mitting devices as to get an exactly equal loss of voltage in two parallel paths including such devices, the consequence being that all the current will flow through one to the exclusion of the other, unless special ballast 35 devices are provided.

The solution of the problem which depends upon introducing ohmic resistance or other choking devices into one or both of the parallel circuits is open to objection on account of the loss of efficiency in the system 40 due to the presence of such devices. By providing means, therefore, for exactly balancing the electro-motive-forces in the two paths without substantial loss of energy, or 45 interference with the regulation or the supply of energy in the system, a substantial improvement in the arc is accomplished.

It is the object of the present invention to supply such means. Broadly, this result is 50 accomplished by introducing into each of the parallel paths means whereby a flow of current in this path produces an electro-motive-force in the opposite path in such a direction as to assist the flow of current in 55 such opposite path. In this way, if the elec-

tro-motive-forces consumed in the two paths be slightly unequal, due to unavoidable lack of similarity in the translating or transmitting devices, the slight increase of current in one path will cause a slight additional electro-motive-force in the second path sufficient to exactly balance the difference in the two electro-motive-forces. In any case, the losses are only those due to the ohmic resistance of the windings and the possible slight hysteresis losses in the iron which may be reduced by appropriate design to a negligible amount.

It should be noted that in normal operation it may be expected that at times current will tend to excess in one of the two or more parallel circuits, in which case an electro-motive-force will be generated in the other tending to equalize the flow. This may continue for some time. Ultimately, 75 however, it may be that current will tend to excess in the other circuit and when this occurs through my invention an electro-motive-force will be generated in the original circuit tending in its turn to equalize the flow.

For the purpose of illustration, I have selected as the devices which it is desired to run in parallel circuits the gas or vapor electrical devices above referred to. For special illustration I have chosen vapor converters 85 which have the quality of permitting current flow in one direction only.

The details of my invention will be understood by reference to the accompanying sheet of drawing.

1 and 2 are the mains of a supply system, the source being any suitable source of alternating currents. The main conductors of the receiving circuit are shown at 3 and 4 and translating devices requiring direct current appear at 5, 5. Any suitable direct current translating devices may be placed in the receiving circuit; or these devices may be omitted.

Between the mains 1 and 3, I introduce two parallel circuits, 40 and 60, which it is desired to operate in parallel. These circuits are here represented as being included in a device of the type of my gas or vapor electric apparatus, consisting of a suitable container inclosing a conducting gas or vapor and provided with a plurality of positive electrode 13 and 14 and a negative electrode 9. Devices of this character have the property of permitting current flow in 110

one direction only, the direction in the present instance being indicated by arrows.

In circuit with the anode 13 is a coil 10 surrounding a laminated core 11; and in circuit with the anode 14 is a coil 12 surrounding the same core 11. In other words, the branch circuit 40, contains the anode 13 and the coil 10, while the branch circuit 60 contains the anode 14 and the coil 12. The direction of current flow is always the same, inasmuch as impulses of opposite direction cannot pass from the supply to the receiving circuit owing to the character of the device.

25 It will be understood that the last named device will be constructed in the first instance to have as nearly the same resistance as possible. To compensate, however, for the unavoidable slight difference in apparatus of this class, I introduce the inductive apparatus consisting of the coils 10 and 12 and the core 11. The relations of the respective coils are such that when the load is evenly divided between the two branches, 30 the opposing inductions of the coils substantially cancel each other. Should the branch 40 begin to take a slight excess of current as compared with the branch 60, the inductive effect produced by the increase of current in the coil 10 would be such as to create an additional electro-motive-force in the coil 11, tending to increase the flow of current in the second branch. By these means a change of load in one branch will

produce counter active effects upon the other branch whereby the fall of potential in the two branches will be maintained practically equal, thereby making it possible to operate the two devices in parallel circuits.

In a divisional application filed by me 40 Serial Number 168,986, filed August 10, 1903, claims are made upon the apparatus described herein.

I claim as my invention:

1. The combination with a vapor electric 45 apparatus comprising an exhausted container, a cathode and a plurality of anodes therefor, of leads for said anodes connected with a supply circuit and choke coils in the respective leads, said choke coils having a 50 common core, together with a lead and return circuit from said cathode.

2. In a system of electrical distribution, the combination with a vapor rectifier comprising an exhausted container, a plurality 55 of anodes and a cathode therefor, of choke coils in the respective anode leads, together with means for supplying alternating potential to said anodes and receiving rectified current from said cathode.

Signed at New York, in the county of New York, and State of New York, this 19th day of May A. D. 1903.

PETER COOPER HEWITT.
